MATCH BOX HOLDER

Isadore H. Dube, Cincinnati, Ohio

Application February 16, 1933. Serial No. 657,148

1 Claim. (Cl. 206—31)

The invention relates to a match box holder and more especially to that type of holder for mounting upon a wall.

The primary object of the invention is the provision of a holder of this character, wherein the body thereof is made from sheet metal stamped and cut to provide a shelf and a back wall so that a match box can be supported thereby, the back wall being provided with retaining means so that the box of matches will be made secure upon the shelf, the box for the matches being provided with an opening permitting the removal of the matches therefrom with dispatch.

Another object of the invention is the provision of a holder of this character, wherein the retaining means involves a pair of prongs, these being forced into the body of the match box under the action of a spring lug cut and bent from the shelf of the holder, while the prongs are cut and bent from the back wall of the holder, so that when the match box is made secure thereon it will not work loose nor will it become displaced from normalcy in the removal of matches therefrom.

A further object of the invention is the provision of a holder of this character which is extremely simple in construction, thoroughly reliable and efficient in its purpose, light in weight, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

In the accompanying drawing:

Figure 1 is a perspective view of a match box constructed in accordance with the invention showing a match box mounted thereon.

Figure 2 is a perspective view of the holder with the match box removed.

Figure 3 is a vertical longitudinal sectional view through the holder and match box, the latter being mounted in the holder.

Figure 4 is a horizontal sectional view through the holder.

Similar reference characters indicate corresponding parts throughout the several views in the drawing.

Referring to the drawing in detail, the match box holder comprises a body A, preferably made from sheet metal, cut and bent to provide a

shelf 5 and a back wall 6 respectively, the wall being at right angles to the shelf, while struck outwardly from the body A throughout the extent of the shelf and back wall are reinforcing ribs 7, these being spaced from each other and parallel to one another, they being extended entirely through the shelf and back wall. It will be obvious that in the use of the holder these ribs 7 throughout the back wall 6 will contact with the support to which the holder is applied, as for example, a wall B of a room or enclosure.

Formed medially of the back wall 6 of the body A are upper and lower countersunk circular portions 8 having suitable apertures for accommodating fasteners 9. These countersunk portions enable the heads of the fasteners 9 to be received therein so as not to protrude beyond the outer face of the back wall 6 of the holder as will be clearly apparent from Figures 2 and 4 of the drawing.

Cut and bent from the ribs 7 close to the upper end of the back wall 6 of the body A is a pair of pointed outwardly curved fingers or prongs 10, these providing retaining members to be engaged in or penetrate the body of the container or match box 11 when the same is placed upon the holder to be held thereby. The shelf 5 has cut and bent therefrom an upwardly curved spring lobe or ear 12 which functions to force the container or box 11 in an upward direction to have the prongs or members 10 penetrate the body of said container or box 11 as is shown in Figure 3 of the drawing for the fastening of said container or box upon the holder without liability of the accidental detachment thereof as should be obvious.

Cut and bent from the back wall 6 of the body A close to the shelf 5 are outwardly extended tongues 13, these having the upper outer corners 14 laterally curved so as to permit the introduction of the container or box 11 between the tongues 13 and guiding the same to the lobe or ear 12 when said container or box is brought into place upon the holder. These tongues 13 also prevent any lateral or side displacement of the box or container 11 when attached to the holder.

The box or container 11 at its front wall is provided with a suitable opening flap 15 which when pulled outwardly to the position as shown in Figure 1 of the drawing will permit access to the matches 16 within said container or box 11 for the removal of the matches therefrom at the option of the user.

2

What is claimed is:

A holder of the character described comprising a single piece of material forming a body bent on itself to provide a shelf and a back wall 5 at right angles thereto, pointed prongs cut and bent from the back wall near the upper end thereof, a spring finger cut and bent from the shelf and acting upon a match box to force the same in a direction for the automatic engage-

10

ment of the prongs therewith when the box is brought in place relative to the body, strengthening ribs struck from the body throughout the longitudinal extent thereof and extending through the shelf and back wall, and tongues cut and bent from the back wall of the body to engage with opposite sides of the match box to hold the same against lateral displacement.
